KNIFE SHARPENER

Filed April 23, 1928

INVENTOR

Abe O. Samuels
Harold E. Stonebraker,
his ATTORNEY

UNITED STATES PATENT OFFICE

ABE O. SAMUELS, OF ROCHESTER, NEW YORK, ASSIGNOR TO SAMSON-UNITED CORPORATION, OF ROCHESTER, NEW YORK, A CORPORATION OF DELAWARE

KNIFE SHARPENER

Application filed April 23, 1928. Serial No. 272,135.

My invention relates to a knife sharpener of the general type employing interlapping rotary disks such as disclosed in Lampert Patent No 1,558,187, and has for its purpose to provide a simple, practicable, and efficient structure which can be manufactured at a low cost

A further object of the invention is to afford a strong, durable arrangement which lends itself to quick, convenient operation at all times, and will stand up under hard constant usage.

To these ends the invention consists in the construction and arrangement of parts that will appear from the following description when read in conjunction with the accompanying drawings, the novel features being pointed out in the claim following the description.

20 In the drawings:

Figure 1 is a side elevation of a knife sharpener constructed in accordance with a preferred embodiment of the invention;

Figure 2 is a bottom plan view;

25 Figure 3 is a top plan view with the handle removed;

Figure 4 is an enlarged side elevation of the base or support, partially broken away;

30 Figure 5 is an end elevation of Figure 4, and

Figure 6 is a sectional view on line 6—6 of Figure 1.

Referring more particularly to the drawing, in which like reference numerals refer to

35 the same parts throughout the several views, the structure is intended more particularly for use in a knife sharpener of the type including two rows of interlapping rotary disks 1 arranged in parallelism as shown in

40 Figure 3. The disks 1 are mounted on supporting pins 2 which are carried by the upstanding vertical walls 3 that are formed at the sides of and integral with one end of the base designated at 4.

45 Said end of the base merges gradually

along a continuous curve into an upwardly inclined opposite end, and such inclined end is bent or rolled transversely upon itself downwardly or oppositely to the direction of the vertical walls 3, thereby affording a 50 stiff tubular-like handle support 5 which is of small cross-section and can be driven into an opening 6 in a wood or other handle 7, the handle being held on the tubular portion 5 by tight frictional engagement.

55 With the construction described, the handle 7 is located at the most convenient angle for holding the sharpener on a horizontal base or table, and the tubular-like portion 5 insures a rigid, stable structure that prevents possible bending or weakening of the handle and affords a device which is sure to give practical and satisfactory service as long as the sharpening disks 1 continue to wear and function. The tubular-like portion 5 60 also permits manufacturing the device at a minimum cost, while affording an economical form of handle support that enables using the sharpener in the most effective and easiest way.

70 While the structure has been described with reference to a specific embodiment, the invention is not confined to the details shown, and this application is intended to cover such modifications or departures as may come 75 within the intent of the improvement or the scope of the following claim

I claim:

75 A knife sharpener consisting of a flat base portion adapted to rest on a plane support, 80 upstanding side walls integral with the base, a series of sharpening disks mounted between said side walls, said base having an extension projecting from one end thereof beyond the side walls and having a central longitudinal upwardly dished portion and side edges that gradually converge and terminate in an integral handle portion that is inclined upwardly from the base portion, said upwardly inclined portion forming a handle 85 90

portion that is generally of inverted U-shape in cross-section, the walls forming the handle portion extending downwardly in a direction opposite to said side walls of the base portion, and a handle surrounding and secured to said handle portion, the handle portion being sharply inclined upwardly to such a degree as to permit conveniently holding the handle of the sharpener when the base is resting on and against a support, a portion of said extension being adapted to rest on the support with the base.

In witness whereof, I have hereunto signed my name.

ABE O. SAMUELS.
